Teletype Corporation, Chicago, Ill., a corpora-
tion of Delaware

Application December 30, 1938, Serial No. 248,539

11 Claims. (Cl. 178—25)

This invention relates to printing telegraph apparatus and more particularly to types of such apparatus capable of tabular recording.

The principal object of the invention is to provide in a keyboard perforator and transmitter means effective in preparing a control strip for controlling telegraphically the recordation of information containing tabular operations.

A feature of the invention is to produce a signal control strip so perforated as to provide variable tabulation time intervals by inserting in the control strip variable pluralities of tabulation time code signals having non-spacing, non-printing attributes.

Another feature of the invention resides in providing in a keyboard perforator transmitter mechanism controlled by the operator, using the tabulator mechanism as an indication, whereby the code signal allotted to the operated function key lever is repeated consecutively a number of times corresponding to the tabulation time.

To achieve the above and other objects of the invention, a keyboard perforator transmitter of the type disclosed in U. S. Patent No. 1,965,572 is modified for the production of perforated tape to be subsequently employed to control the transmission of message matter embodying tabulation operations.

In printing telegraph systems employing recording apparatus provided with tabulating mechanism, a variable interval of time is required to move the type carriage (or platen carriage, as the case may be) from one tabular position to another. This interval will here be termed "tabulating time." In the manual operation of key controlled recording apparatus, cognizance is taken of tabulating time by the operator, who, during such time, refrains from operation of the keyboard. However, in automatic operation of such recording apparatus under remote control of tape transmitters wherein the apparatus is unattended for considerable periods of time, it is desirable to reproduce the effects of manual control during tabulation so as to maintain a tabulating condition automatically during the time that the carriage is in motion while tabulating, thus attaining proper tabular operation of the recording apparatus.

The present invention provides for the operative association of a keyboard perforator transmitter with a receiving printer, whereby the receiving printer may be made to respond to the operation of the keyboard transmitter simultaneously with the perforation of a tape. Such an arrangement produces a printed copy or home

record corresponding to the perforations in the tape.

Specifically, when a perforated record is made which involves tabulated portions, it is expedient to compensate for the tabulation time required at the recorder, either by suspending transmission during tabulation, as disclosed in U. S. Patents Nos. 2,104,071 and 2,104,110, or by employing the arrangement or methods according to the present invention, which continues transmission but suspends printing. As in the type of tabulating recorder disclosed in U. S. Patents 2,104,071 and 2,104,110, a tabulator bar extends across the front of the machine, is carried by brackets mounted in the typing unit, and is capable of swinging toward and away from the type carriage. The tabulator bar carries a number of adjustable stop members which determine the positions to which the type carriage is automatically propelled (each of which distances is equivalent to a plurality of character spaces) following the reception of a tabulator code signal combination.

According to the method embraced by this invention, a means is provided for blocking the tabulator function lever after one selective operation thereof, and a device is provided which produces repeat perforations of the tabulator code combination in the tape. The arrangement is responsive to the tabulator signals for blocking the tabulator function lever after one operation and for holding the function lever blocked during the time required to move the type carriage during tabulation. The blocking mechanism is reset when a character is transmitted utilizing thereby a complete forward stroke of the printing bail. Briefly, the holding of the tabulator key depressed provides repeat perforations of the tabulator combination in the tape, which, when the tape is sent through the transmitter distributor, will consume the required amount of line time for the carriage to tabulate from one stop to the next. When the carriage has come to rest at the new position, the printing of a character, or merely spacing one space, will reset the mechanism.

A better understanding of the present invention may be had from the following description taken in conjunction with the accompanying drawings wherein like reference characters are used to designate similar parts throughout the several views, and wherein:

Fig. 1 is a front elevational view partly in section of a keyboard perforator and transmitter embodying the present invention;

Fig. 2 is a sectional plan view of the apparatus shown in Fig. 1;

Fig. 3 is a cross-sectional view taken substantially on line 3—3 of Fig. 1;

5 Fig. 4 is a fragmental perspective view of the arrangement according to the present invention;

Fig. 5 is a schematic electrical diagram of the perforator magnet operating circuit;

10 Fig. 6 is a detailed sectional view taken on line 10 4—4 of Fig. 1; and

Fig. 7 is a sectional view taken on line 7—7 of Fig. 1 showing the arrangement according to the present invention in one of its operative positions.

15 Having reference to Fig. 1, there is shown a receiving printer of the type disclosed in U. S. Patent No. 1,904,164 to which is associated a tabulator mechanism and control means therefor, a keyboard, a perforator, and a transmitter. This 20 combined apparatus comprises a base portion, indicated generally by the numeral 11, upon which is mounted a typing unit, indicated generally as 12. Associated with the base portion 11 is a perforator, indicated generally 13, and a transmitter, indicated generally 14.

25 Positioned at the rear of the base portion 11 is a pivot rod 15 (Fig. 1), which extends transversely of the base portion. On the pivot rod 15 a plurality of key levers 16 are rotatably mounted which are normally urged upwardly by individual springs (not shown) and which are provided, as is the usual practice, on the forward end with keys (not shown) arranged in banks. Beneath the key levers 16, and extending transversely thereof, are a plurality of pairs of permutation bars 19 and 21. As is well known, the 30 number of pairs of permutation bars corresponds to the number of elements in the permutation code; for example, five or six. The permutation bars 19 and 21 are provided at each end with vertical slots or notches 22 and 23, respectively, which fit over guides 24 and 25. The bars 19 and 21 are thus held against longitudinal movement, but are free to be shifted vertically in response 35 to the operation of key levers 16.

40 Pivotaly mounted on rods 26 and 27 are a pair of rocker arms 28 and 29 interposed between each pair of bars 19 and 21. The rocker arms 28 and 29 are substantially T-shaped, with their free ends formed with offset lugs on opposite sides of the pivot rods 26 and 27 and spaced some distance therefrom, one of the lugs of each rocker arm projecting forwardly beneath the lower edge of the corresponding permutation bar 21, and its other lug projecting rearwardly beneath the companion permutation bar 19. With 45 this arrangement, the depression of either permutation bar of the pair of bars 19 and 21 rocks the arms 28 and 29 and lifts the companion permutation bar. To the depending portion of each T-shaped rocker arm 28 and 29 is pivotally articulated a longitudinally movable link 31. Thus, when the permutation bars 19 and 21 are moved vertically in accordance with the depression of a key lever 16, the link 31 individual to a pair of the permutation bars 19 and 21 is moved longitudinally.

50 Each of the key levers 16 is arranged, when operated, to engage and depress one of the permutation bars of each pair of permutation bars 19 and 21 and to set these permutation bars in accordance with a character code combination. The upper edges of permutation bars 19 and 21 are variously notched to provide high and low 55 portions in accordance with the respective code

signals. Also, the bars of each pair of permutation bars 19 and 21 are complementary; that is, the notches of one bar are opposite the projection of its companion bar. The interconnection between the bars of each pair of bars 19 and 21 by means of the rocker arms 28 and 29 prevent the simultaneous depression of two key levers. If an attempt is made to operate more than one key lever, the key levers can only be depressed for a short distance, when they will be 10 blocked by the high portions of the permutation bars 19 and 21. By this construction, the simultaneous depression of two key levers and the transmission of an incorrect signal is prevented.

15 The perforator 13 comprises a set of code punches 32 movable through an opening in upper and lower guide plates 33 and 34, and cooperative with a guide plate 35 to perforate the tape 36. The plates 33 and 35 are spaced apart to form a tape guide. Intermediate the guide plates 20 33 and 34 is a stripper plate 37 which cooperates with shoulders on the code punches 32 and on a feed hole punch (not shown), and due to the action of springs 38 operates to remove the punches 32 clear of the tape following the operation of a punch hammer 39. The code punches 32 are selectively operated by the actuating member or punch hammer 39 and a set of interponent bars 41 corresponding in number to the code punches 32. An interponent is, of course, provided for the feed hole punch (not shown), but this interponent is permanently in register therewith. Operatively associated with each of the bars 41 is a pivoted arm 42 which is connected to a link 31 by means of a connecting bar 43.

25 The hammer 39 rocks about its pivot 44 and forms the armature of an electromagnet 45. The interponents 41 are adapted to slide on the hammer 39. When the perforating magnet 45 is unenergized, the hammer 39 is retained in its counterclockwise position by a spring 46. Punch hammer 39 carries at the left end thereof a pawl member 47 which cooperates with ratchet teeth 48 of a spacing roller 49, which is also provided with feed pins 51 adapted to mesh with the feed holes which are invariably perforated in the tape 36. Thus, when the magnet 45 is energized and the hammer 39 is rocked to its clockwise position, pawl 47 is raised to engage a tooth 48 on the spacing roller 49. Then, upon the deenergization of magnet 45, spring 46 actuates the hammer 39 to its counterclockwise position and draws the pawl 47 downwardly, which movement causes the spacing roller 49 to be rotated counterclockwise one angular step to effect the spacing of the tape 36 one unit distance.

30 To insure complete operation of the perforating magnet 45 upon each depression of a key lever 16, a positive latch control for the perforator operating contact is provided which is adapted to be automatically released only upon the complete or effective energization of the perforator magnet. In addition to the five (or six) pairs of permutation bars 19 and 21, there is provided an additional bar 40 (Fig. 4), the link 31 of which is connected by a bar similar to 43 to a contact operating lever 50 (Fig. 1). Associated with contact operating lever 50 is the pair of contacts 52. In the unoperated position of the apparatus, the contact operating lever 50 is held in its clockwise position by a spring 53, which constitutes also a return spring for the universal bar 40, and through control of an insulated striker the contacts 52 are held open. Then, upon the operation of a key lever 16, the contact op- 35 40 45 50 55 60 65 70 75 80 85 90 95 100

erating lever 50 is operated counterclockwise to close the contacts 52, and at its end 54 it becomes engaged by a latch lever 55, thus latching the contacts 52 closed. When the magnet 5 45 becomes energized, and its armature is attracted to rotate the print hammer 39 clockwise, an adjustable striker 57 carried on a bracket 58 integral with print hammer 39 acts upon arm 59 of latch lever 55 to rock the latch lever 55 10 counterclockwise, thus disengaging said latch from the end portion 54 of lever 50, whereupon lever 50 is rocked clockwise by its spring 53 to permit contact 52 to open. It is thus seen that with this anti-chatter arrangement, the energizing 15 of the clutch magnet 45 may not be affected by a tremulous touch on a key lever 16 since, as soon as the key has been depressed to close contact 52, the latch lever 55 acts immediately to maintain said contact 52 in the closed position, 20 whereafter they will be opened only upon energization of magnet 45 and operation of hammer 39 through the cooperation of striker 57 and arm 59.

When the perforating mechanism 13 is employed in combination with the keyboard transmitter 14, the permutation links 31 are each provided with a pair of upstanding guide lugs 61. Interposed between each pair of lugs 61 is a depending arm of a locking latch 62, pivoted on 25 a common rod 63. In this manner, locking latches 62 are pivotally articulated to the permutation links 31 and are adapted to be rocked about pivot rod 63 between either of two positions. Associated with latches 62 are a corresponding series of contact levers 64 for making and breaking individual contacts 65. Each contact lever 64 cooperates with a contact cam 66, individual thereto, mounted on a transmitting shaft 67 which is provided with a clutch mechanism 68 (Fig. 4) controlled by a trip member 40 56 operatively connected to a universal bar member 69, as set forth in U. S. Patent No. 1,965,572.

The cams 66 are assembled as a unit together with the collar 68, the end of which is serrated, 45 and is normally urged along the shaft 67 to the right, as viewed in Fig. 4, by a spring 71. Secured to the shaft 67 and arranged to cooperate with the collar 68 is a similarly serrated collar 72. The shaft 67 is operatively connected through 50 suitable gearing to the main drive shaft 90 mounted in the typing unit 12. The main drive shaft 90 derives its power through a gear 96 and pinion 97 from a motor 98. Thus, the shaft 67 is connected to a source of driving power, comprising the motor 98 in a manner such that 55 it is driven continuously, but due to the arrangement of the collars 68 and 72 which constitute a clutch between the shaft 67 and the cams 66, the latter may be selectively rotated.

60 The spring 71 tends to move the collar 68 along the shaft 67 and into engagement with the collar 72, but this action of the spring is normally prevented by means of a pivoted arm or trip member 56 which is spring urged into the 65 path of a shoulder 73 formed on the collar 68. The shoulder 73 is also formed with a gradual camming surface so that as the collar 68 rotates it will cooperate with the associated portion of the stop arm 56 and cause the collar 68 70 to be moved along the shaft 67 against the action of spring 71 to disengage the serrated portions of the collars 68 and 72 and stop the rotation of the collar 68 and its associated cams 66. Trip member 56 has a horizontal portion 74 75 which is operatively associated with one arm of a

T-shaped lever 75, the depending arm of which is pointed as at 76, and which is normally in the path of a shoulder 77 formed in a trip-off pawl member 78. The member 78 is linked to the universal bail 69 which is rotatably mounted 5 on trunnions 79, and which is rocked upon the depression of any of the keys of the keyboard.

The universal bail 69 and the member 78 are normally biased to a position shown in Fig. 4 by a spring 81, one end of which is fastened to 10 the member 78, and its other end is secured to a stationary bracket (not shown). When the universal bail 69 is depressed, the member 78 against the action of spring 81 will be moved to the left as viewed in Fig. 4, and the shoulder 77 will engage the pointed end 76 of the T-shaped lever 75 and cause the member 56 to be moved, through the depression of portion 74, out of engagement with the shoulder 73 of collar 68. Under these conditions the spring 71 urges the collar 68 to 15 the right, as viewed in Fig. 2, and the serrated portions of the collars 68 and 72 are brought into engagement with each other so that the power from shaft 67 is effective to rotate the cams 66 through one complete cycle. When the 20 cams 66 approach the end of their cycle of rotation, the cam surface preceding the shoulder 73 is effective with the trip member 56 to move the collar 68 against the action of spring 71 and effects the disengagement of the serrated portions of the collars 68 and 72. 25

The universal bail 69 is urged to its normal position by spring 81 so that the member 78 will likewise be urged to its normal rightward position. Due to the action of a trip-off pawl 35 eccentric 60 in camming the shoulder 77 of trip-off pawl 78 out of engagement with the end 76 of member 75, the latter will be restored to its normal position invariably for each operation of the keyboard mechanism, thus providing a 40 non-repeat mechanism. However, in some instances it is desired to continue the rotation of the cam assembly 66 for a longer period, as previously mentioned as one of the objects of the present invention, and for a period sufficient to 45 transmit successively a plurality of groups of impulses of the same character. In order to achieve this result, there is associated with a space bar loop 82, a member 83, which is fastened to a rod 84, on which the space rod 82 is loosely mounted. Member 83 is provided with a forwardly extending portion 85 having a laterally disposed end 86 adapted to be disposed beneath the space bar loop 82. Member 83 is also provided with a vertically extending portion 87, to the upper extremity of which is connected a rod 88. The rod 88 has a horizontally extending reverted portion 89 which is normally in alignment with the downwardly extending portion of the T-shaped member 75. Consequently, when the space bar loop 60 82 is depressed, it will act through extremity 86 of arm 85 of member 83 to move the rod 88 to the left, as viewed in Fig. 4, and the portion 89 will engage the downwardly extending portion of the T-shaped member 75 and cause its rotation and the corresponding rotation of stop member 56 for releasing cams 66 for rotation. The T-shaped lever 75 will be held in a position to retract the stop member 56 from cooperation with shoulder 73 and the cams 66 will be rotated 65 through successive cycles as long as the space bar 82 is held depressed. 70

In order to repeat a code combination identified with a particular key, for example the tabulator key as will appear hereinafter, the space 75

bar mechanism of the apparatus according to the present invention is shown, as indicated in Fig. 4, with an arm 91 fixed to the rod 84. The arm 91 is provided at its extremity with a laterally extending portion 92 which, according to the present embodiment, is located below the key lever 93 identified with the tabulator combination.

In the operation of the transmitting unit 14, the depression of a key lever 16 moves the permutation bars 19 and 21 permutably in accordance with a predetermined code combination, the setting of which, through link 31 determines the position of the locking latches 62. The rotation of the cams 66 is initiated substantially simultaneously with the setting of the locking latches, through the instrumentality of trip member 56, which is acted upon under the control of the universal bar 69. A locking loop 94 (Fig. 1), controlled by a cam 99, carried on the shaft 67, is permitted to rotate in a counterclockwise direction, as viewed in Fig. 1, to lock the latches 62 in their selected positions. The setting of latches 62 determines whether the contact levers 64 shall or shall not be operated by their associated cams 66 to transmit, through contacts 65 over a signal line 95 to the receiving station, a predetermined code combination of signaling impulses. Incidentally, included in the line circuit is the receiving magnet 10 of the home recorder, exemplified by the typing unit 12 of the present embodiment, so that the signals transmitted over the line 95 will also cause a printed record to be made of the matter which is perforated in the tape 36. The respective notches in the cams 66 are arranged in a helical progression so that upon the rotation of the cam assembly, the contacts 65 controlled by levers 64 will be operated successively in accordance with the code to be transmitted. The apparatus herein disclosed is operated in accordance with an equal length letter code in which each code combination is a permutation of marking and spacing conditions and is preceded by a start impulse and followed by a stop impulse according to the well-known start stop system.

When the perforator and transmitter are to be operated simultaneously under the control of a key lever 16, means is provided for starting the operation of the perforating device under control of the transmitting devices to insure that the same signal that is transmitted is also invariably perforated in the tape. To achieve this result, two pairs of contacts 101 (Fig. 1) are positioned over two adjacent transmitting cams 66, as more fully disclosed and described in co-pending application Serial No. 167,139 filed October 4, 1937 by R. A. Lake. The pairs of contacts 101 are mounted on a bracket 102, and associated with each pair of contacts 101 for controlling the operation of the same is a cam follower 103 or 104. In this manner, cam followers 103 and 104 ride into the depression of their associated cam 66, which are the same depressions which act to operate the contact levers 64. The purpose of having two pairs of contacts 101, which are connected in parallel (as shown in Fig. 5) is to impress a longer operating impulse of the perforating magnet 45 than would be obtained under the same conditions by a single pair of contacts. The contacts 101 are normally open, and when the transmitting cam distributor (comprising cams 66 and contacts 65) is operated, the circuit for the perforator magnet 45 will invariably be closed for the period of sub-

stantially two impulse intervals because of an overlap in the sequential operation of the pairs of contacts 101.

The keyboard mechanism shown in Fig. 1 is similar to that described and shown in U. S. Patent No. 1,965,572. With the mechanism shown in said patent, it is desired in some instances to transmit directly to a line circuit code combinations of impulses representative of the character key operated, while in other instances it may be more practical first to perforate the tape in accordance with the key operated, and then to transmit subsequently the signals corresponding thereto by subjecting the tape to a tape transmitter. To provide for the several possible conditions of operation of the mechanism, a switch is arranged in the keyboard apparatus to control the transmission of impulses directly to the line circuit, the perforation of tape only, or the operation of the transmitting distributor and the perforator simultaneously.

To control these various operations, a switch lever 105 (Fig. 1) is provided which is mounted adjacent the transmitting distributor 14. Lever 105 assumes three positions; namely, an upper position 106A (Fig. 5), a middle position 106, and a lower position 106B, and is held in any one of these positions through the cooperation of a detent bracket 107 (Fig. 1). As shown in Fig. 5, switch member 105 is provided with a bifurcated end having strikers which cooperate with a group of five contacts 108. The position of the switch member 105 indicated at 106A is known as the "keyboard" position, and is a position wherein only direct keyboard transmission of signals to the line is effected; that is, each time a key lever is operated, the transmitting cam drum is rotated a single cycle to transmit a code combination of signals through contacts 65 to the line 95. In this position of member 105, all of the five contacts of contact bank 108 are opened.

The position of switch member 105, indicated as 106, is known as the "tape and keyboard" position, and is that condition of the apparatus wherein the perforator and transmitting mechanisms are operated simultaneously. In this position, the contacts of the contact bank 108 are arranged, as shown in Fig. 5, wherein the lower contact 112 remains closed, and in this position the energizing circuit for the perforating magnet 45 extends from positive battery over conductors 109 and 111, through contact 112, through contacts 101 associated with the transmitting cams, then over conductor 113, through the winding of the perforating magnet 45, then to negative battery. From the previous description it is observed that contacts 101 are closed periodically, once for each cycle of rotation of the transmitting cam drum. In this manner, the operation of the perforator magnet 45 is assured. The position of the switch member 105 indicated in Fig. 5 as the 106B, is known as the "tape" position, and in this position, the automatic tabulating mechanism is not used.

Referring particularly to Fig. 2, a motor 98 supplies power, through a pinion 97 and gear 96 to the main operating shaft 90 of the typing unit 12. Shaft 90 carries a portion of the spacing mechanism of the printing apparatus, indicated generally as 114, and the selector cam assembly, indicated generally as 115. As is known in this type of apparatus, power is communicated from the motor 98 to a cam assembly, indicated generally as 116, through the instrumentality of a grab clutch 117. Portion 118 of grab clutch 75

117 constantly rotates with the shaft 90, which has also frictionally connected thereto the escape wheel and gear of the spacing mechanism 114, and the selecting cam drum 115. Portion 118 is adapted to be cooperatively engaged with the driven portion 119 of clutch 117 when a throw-out lever 121 is operated, in timed relation with the reception of code signals, from a cam on the cam drum 115.

10 The spacing mechanism is fully described in Patent No. 1,904,164 and is illustrated in Fig. 19 therein and controls, through gear 122, shaft 123, gear 124, and rack 125 (Figs. 2 and 3), the movement of type carriage 126 to form character spaces, acting in this movement to wind up a carriage return spring (not shown).

Positioned parallel to the main operating shaft 90 is a rock shaft 127 (Fig. 3) on which are carried various mechanisms; for example, printing bail 128 and function lever bail 129, and the escapement pawls of the spacing mechanism 114. The printing bail 128, which is actuated by a printing spring 131 (Fig. 2) in proper timed relation in the operating cycle, functions to reciprocate a pull bar operating member 132 (Fig. 3) to cause the operation of a type bar 133, as fully described in Patent No. 1,904,164. As more fully described in the latter patent, the selector magnet 10 in response to code signal impulses (impressed on the signal line 95 by the cam distributing contacts 65) controls through the selecting cam assembly 115, a series of elements 134 (Fig. 2) which are articulated to a corresponding plurality of selector vanes 135 of the selector vane assembly 136. The setting of the selector vanes 135 in accordance with a received code combination of impulses is transferred through a series of bell cranks 137 to a series of code bars 138 carried in the type carriage 126 which is movable longitudinally with respect to a stationary platen, indicated generally as 139, Fig. 3.

The selector vanes 135, as set forth in Patent No. 1,904,164, control a series of function levers, indicated generally as 140 (Fig. 3) among which are the function levers 141, 142, and 143 particularly concerned with the present invention.

According to the present invention, the keyboard perforator and transmitter of the type disclosed in U. S. Patent No. 1,965,572 is modified for the production of perforated tape to control the transmission of message matter embodying tabulation operations. To achieve this result, the tabulating mechanism which is in accordance with U. S. Patent No. 2,076,864 comprises a tabulator bar 144 extending in front of the printing apparatus, as shown in Fig. 1, and which is provided with depending portions 145 and 146, by means of which it is pivotally mounted on a bracket 147 carried in the printer frame. The tabulator bar 144 is swingable toward and away from the type carriage 12, and is also provided with a longitudinal slot 148 extending substantially the entire length of the bar, within which are carried adjustable stop members 149, which are clamped to the bar 144 by means of the screws 151 (Fig. 4) and clamping members 152. As indicated in Fig. 6, these stop members 149 are provided with an inclined or cam portion 153, conformed to produce a quick camming-out action upon cooperating with a cam element 154, carried by the type carriage 12, to terminate the tabulating operation.

Tabulator bar 144 is also provided, intermediate the depending portions 145 and 146, and

suitably positioned relative to tabulator function lever 142, with another depending portion 155. Attached to and depending from portion 155 is a bar 156, the lower end of which is provided with an aperture 157 (Figs. 3 and 4) having its upper right-hand corner formed so as to provide a re-entrant stepped portion 158. The tabulator bar 144 normally tends to move in a clockwise direction, as viewed in Fig. 4, due to the action of a spring 159.

10 Cooperating with the stepped portion 158 is one arm 161 of a lever 162 pivoted at 163. The extremity of arm 161 is provided with a laterally disposed portion 164 which cooperates with portion 158 of the member 156. At the end of arm 165 of the lever 162 is carried a vertically extending member 166, the upper end of which is provided with an open ended slot adapted to engage a pin 167 carried by the upper escapement pawl 168 of the spacing mechanism 114, 20 which is fully described and shown in U. S. Patents 1,904,164 and 2,076,864.

As previously mentioned, the selector vanes 135 control a series of function levers 141, 142, and 143, including the tabulator function lever 142. Function lever 142 is provided on an arm 169 thereof with code notches and projections which cooperate with the vanes of the selector vane assembly 136, and which are coded to correspond with the tabulator signal. Thus, when 30 the vanes 135 are set according to the tabulator signal in response to the operation of the selector mechanism 10, the tabulator function lever 142 will be selected and will be rotated toward the selector vanes 135, by an individual spring 35 171, about its pivot rod 172.

Normally, however, as set forth in Patent No. 1,904,164, the function levers 140 are restrained against action, by their springs 171, by the function lever bail 129 acting through rod 130 on arms 150. The function lever bail 129 is provided with upturned edges 120 which are adapted to span certain of the function levers 140 wherein it is desired to prevent printing and/or spacing operations, this being effected by permitting arms 150 of such function levers to intercept the upturned edges 120 after only a limited movement thereof, sufficient to prevent the printing and spacing functions. Of course, the rod 130 of the function lever bail 129, due to its camming action on the inner surface of arms 150 invariably returns the function levers 140 to their normal or unoperated position.

Function lever 142 is provided with a horizontal portion 173, so conformed that its extremity 174 engages the lower edge of arm 165 of lever 162 so that, when function lever 142 (upon its selection) is permitted to rotate in a counterclockwise direction under the action of its spring 171, the end 174 thereof is raised, thus rotating the lever 162 against the tension of its spring 175 (Fig. 4).

The laterally disposed end 164 of lever 162 is thereby moved downwardly clear of the stepped portion 158, permitting spring 159 to urge the tabulator bar 144 inwardly (or clockwise as viewed in Fig. 4) until wall 176 of member 156 engages the laterally disposed portion 164. Adjustable stops 149 are moved inwardly into the path of the cam member 154 (Fig. 6), which is pivoted at 177 on a portion 178 integrally formed on a bar 179 (which is comparable to bar 53, shown in Fig. 1 of Patent No. 1,904,164) and which is employed for retaining the bell crank levers 137 in operable relation to the vanes 135.

Cam 154, like bar 179 and bell crank 137, is movable with the type carriage 126 for carriage spacing, and normally tends to rotate in a clockwise direction about pivot 177 due to the action 5 of a spring 191, but its clockwise rotation is limited by the coaction of a stop pin 192, carried thereon, with the end of bar 179. Consequently, upon the rightward movement of type carriage 126, as viewed in Fig. 1, cam 154, due to its limited 10 rotatability in a clockwise direction, will, by its camming action of stop members 149, rock the tabulator bar 144 outwardly; thus, upon a leftward movement of type carriage 126, cam 154 upon striking the series of stop members 149, 15 will be rotated counterclockwise against the action of spring 191, avoiding operation of the cam portion 153. When the tabulator bar is thus actuated outwardly by the cam 154, against the action of spring 159, the laterally disposed 20 portion 164 of lever 162 will escape the stepped portion 158 and, through the action of spring 175, will resume its upward position shown in Figs. 3 and 4.

Such is the operation of the tabulator mechanism in response to a tabulator code signal combination. In the preparation of a perforated tape to be used for controlling the transmission of messages embodying tabular matter, it is necessary to take cognizance of the time required 25 to move the carriage from one tabular position to another. According to the present invention, this is effected by inserting in the perforated tape variable pluralities of tabulation-time code combinations of perforations having non-spacing, 30 non-printing attributes. Specifically, the particular non-spacing, non-printing code combination chosen to exemplify the present invention is the tabulator signal, and a device is provided which produces repeat perforations of the tabulator 35 combination in the tape, so that upon the subsequent transmission of said plurality of tabulation signals, the tabulating mechanism of the receiving printer will respond to the first of said tabulator signals, not only to initiate the movement 40 of the type carriage for tabulation, but also to operate a means for blocking the tabulator function lever after one selective operation thereof. Thus, the reception of successive tabulation signals, after the first, will have no effect on the 45 tabulating mechanism.

According to the specific embodiment of the invention exemplified in Figs. 2, 3, and 4, a spring mounting plate 181 (comparable to spring bar 178 in Fig. 6 of Patent No. 1,904,164) is secured 50 to bracket 147 and comprises an integral platform 182 on which are mounted levers 183 and 184, and a slide 185. The lever 183 is pivoted at 186, and one arm thereof terminates in an extension which cooperates with the function lever 60 142, so that when the function lever 142 is actuated to its selective position by its spring 171, it rocks the lever 183 clockwise about its pivot 186 to remove the shoulder 187 out of engagement with slide 185. The slide 185 is thereupon actuated 65 leftwardly (as viewed in Fig. 2) by a spring 188, distended between the slide 185 and an extension on lever 183, until a projection 189 on the slide 185 is ultimately presented in front of the function lever 142, thus acting to block or 70 prevent the selective movement of the function lever 142 in response to successive tabulation code signals. Actually, however, when the function lever 142 is selected, it rocks lever 183 clockwise to free the slide 185 for leftward movement 75 by its spring 188, but while function lever 142 is

still in registry with the selector vanes, the slide 185 only moves leftwardly until its projection 189 strikes the side of lever 142, then when the function lever 142 is retrieved by the function lever bail 129 and is returned to its position shown in Fig. 3, the projection 189 is clear of the function lever 142, and the slide 185 is free to move leftwardly the remaining distance to present projection 189 into the path of function lever 142. The righthand arm of lever 183 is offset to clear projection 189 so as to permit the leftward movement of the slide 185. Thus, the elements 183, 184, and 185 assume the relative positions shown in Fig. 7. Adjacent to the function lever 142 is a function lever 141 which is provided with code notches corresponding to the function lever 142. However, function lever 141 is not provided with a rearwardly extending portion similar to 173. The purpose of function lever 141 is to block or prevent (due to the blocking relationship between 20 edge 120 and arm 150) the performance of the printing and spacing functions during the reception of the plurality of tabulator code signals after the first signal. This is necessary since the function lever 142 is blocked against operation by projection 189 and is non-responsive to the succeeding tabulator signals after the first tabulator signal and it is desirable to prevent printing during the reception of said plurality of tabulator signals. Therefore, the auxiliary lever 141 25 is provided to perform this function of blocking the printing operation normally effected by the function lever 142. After the function lever 141 has responded to all of the series of tabulator code signals representing the tabulation time, the elements 183, 184, and 185 are reset to their normal position, shown in Fig. 2, by the operation of a function lever 143 which responds to the reception of any character code signal or a spacing code signal. In other words, function lever 40 143 is a universal function lever and is not provided with any code notches, and is actuated toward the vanes 135 by its spring 171 upon any operation of the printer which permits a full stroke of the function lever bail 129.

With the arrangement just described, tabular matter is prepared in tape in the following manner: The printer set is operated with the tape-keyboard key 105 in the tape and keyboard position, which is the position indicated 106 in Fig. 5. 50 In the operation of the printing, tape perforating and transmitting mechanisms simultaneously, the printed record appears on the page of the printer simultaneously with the perforated record on the tape 36. It is understood, of course, that the tabulation stops 149 have been arranged in a predetermined manner prior to beginning of the printing operations. When it is desired to tabulate, the tabulator key lever 93 is held depressed until the carriage travels to the next 60 tabulator stop 149 and is observed by the operator to come to rest. Holding the key depressed in this manner, provides (through lever 91, rod 84, arm 87, and rod 38) repeat operations of the 65 transmitting cams 66 and consequently, through contacts 101, repeat perforations of the tabulator code combination in the tape 36 which, when the tape is sent through a tape transmitter, will consume the required amount of line time for the 70 carriage 126 to tabulate from one stop 149 to the next without stopping the tape transmitter. When the carriage 126 has reached its new position, the printing of a character or merely spacing one space will reset the mechanism shown in 75

Fig. 7, so that the operator may then tabulate to the next tabulator stop position, if desired.

When the tape 36, so prepared, is used for tape transmission to a printer having the typing unit 5 of the form indicated 12 in Fig. 1, the first tabulator code combination in the plurality of tabulation code combinations is effective to select the tabulator function lever 142, which through its portion 173 rocks the lever 162 counterclockwise 10 (Fig. 4) to bring the portion 164 beneath the shoulder 158 and simultaneously through arm 166, to disengage pawl 168 of the spacing mechanism to permit continuous spacing. At the same time, function lever 142 acts upon lever 183 to 15 effect its disengagement from slide 185 so as to present the extension 189 into the path of the function lever 142 to block the same during the reception of successive tabulator code signals. This renders the tabulating mechanism of the 20 printing apparatus ineffective for any but the first of a series of tabulation code signals. Then, when the carriage comes to rest after tabulation, the normal operation of the printing apparatus thereafter in response to a character code signal 25 or a space code signal will permit the function lever bail 129 to make a full stroke, and accordingly permit the operation of the universal function lever 143, which, when operated, will act upon lever 164 to rotate said lever counterclockwise 30 to bring the slide 185 to its rightward position into engagement with the shoulder 187 on lever 183.

Although a particular embodiment of the invention has been described herein, it will be understood that the apparatus is capable of many modifications, and it is contemplated that all changes which come within the range and scope of equivalency are intended to be embraced within the purview of the appended claims.

40 What is claimed is:

1. In a telegraph printer, a carriage, spacing mechanism effective upon said carriage to produce letter spacing, a plurality of function code levers, tabulating mechanism operative in response to the selective operation of a certain one of said levers to control the advancement of said carriage through a predetermined plurality of spaces at a time, and solely mechanical means to prevent the consecutive operation of said certain 50 one of said levers.

2. In a telegraph printer, a carriage, character spacing mechanism effective upon said carriage to produce letter spacing, a plurality of function code levers, tabulating mechanism operative in response to the selective operation of a certain one of said levers to control the advancement of said carriage through a predetermined plurality of spaces at a time, and means operated by said certain one of said levers to prevent the consecutive operation thereof.

3. In a telegraph printer, a carriage, spacing mechanism effective upon said carriage to produce letter spacing, permutation code mechanism to control operations other than recording comprising a plurality of function code levers, tabulating mechanism operative in response to the selective operation of a certain one of said levers to control the advancement of said carriage through a predetermined plurality of spaces at a time, means to prevent the consecutive operation of said certain one of said levers, and means effective under certain operating conditions to render said preventing means ineffective.

4. In a telegraph printer, a carriage, spacing mechanism effective upon said carriage to pro-

duce character spaces, permutation code mechanism to control operations other than recording comprising a plurality of function code levers, tabulating mechanism operative in response to the selective operation of a certain one of said levers to control the advancement of said carriage through a predetermined plurality of spaces at a time, and automatic means to prevent the consecutive operation of said certain one of said levers.

5. In a telegraph printer, a carriage, spacing mechanism effective upon said carriage to produce character spaces, permutation code mechanism to control operations other than recording comprising a plurality of function code levers, tabulating mechanism operative in response to the selective operation of a certain one of said levers to control the advancement of said carriage through a predetermined plurality of spaces at a time, and means comprising a blocking element and a pair of control levers therefor effective in response to a non-printing condition to block said certain one of said levers against operation and effective in response to a printing condition to restore said blocking element to its unblocking position.

6. In a telegraph printer, a carriage, spacing mechanism effective upon said carriage to produce character spacing, permutation code mechanism to control operations other than recording comprising a plurality of function code levers, tabulating mechanism operative in response to the selective operation of a certain one of said levers to control the advancement of said carriage through a predetermined plurality of spaces at a time, means controlled by said certain one of said levers to prevent the consecutive operation thereof, and means controlled by another of said levers to render said means ineffective.

7. In a telegraph printer, a carriage, spacing mechanism effective upon said carriage to produce character spaces, permutation code mechanism to control operations other than recording comprising a plurality of function code levers, tabulating mechanism operative in response to the selective operation of a certain one of said levers to control the advancement of said carriage through a predetermined plurality of spaces at a time, a blocking element, a control lever therefor effective in response to a consecutive operation of said certain one of said levers to render said blocking element effective to block said certain one of said levers, and means effective under certain operating conditions to restore said blocking element to its unblocking position.

8. In a telegraph printer, a carriage, spacing mechanism effective upon said carriage to produce letter spacing, permutation code mechanism to control operations other than recording comprising a plurality of function code levers, tabulating mechanism operative in response to the selective operation of a certain one of said code levers to control the advancement of said carriage through a predetermined plurality of spaces at a time, a slide comprising a blocking instrumentality, a pair of control levers for said slide, means effective in response to the actuation of one of said control levers by said certain one of said code levers to move said instrumentality into register with said code lever to prevent the consecutive operation of said code lever, and means operative on the other of said control levers for rendering said instrumentality ineffective.

9. In a telegraph recorder, a carriage, a spacing mechanism effective upon said carriage to produce letter spacing, a plurality of function levers, tabulating mechanism operative in response to the selective operation of a certain one of said function levers to control the advancement of said carriage through a predetermined plurality of spaces at a time, a blocking instrumentality, and means operated by said certain one of said function levers to render said instrumentality effective to prevent the consecutive operation of said certain one of said function levers.
10. In a telegraph recorder, a carriage, a spacing mechanism effective upon said carriage to produce letter spacing, a plurality of function levers, tabulating mechanism operative in response to the selective operation of a certain one of said function levers to control the advancement of said carriage through a predetermined plurality of spaces at a time, a baffle member, and means operated by said certain one of said function levers to render said baffle member effective to prevent the consecutive operation of said certain one of said function levers.
11. In a recorder, a carriage, spacing mechanism effective upon said carriage to produce letter spacing, a plurality of function levers, tabulating mechanism operative in response to the selective operation of a certain one of said function levers to control the advancement of said carriage through a predetermined plurality of spaces at a time, a slide comprising a blocking instrumentality, a pair of control levers, resilient interconnection between said slide and one of said control levers, pivotal articulation between said slide and the other of said control levers, means whereby said resilient interconnection is rendered effective to move said instrumentality into register with said one of said function levers to prevent consecutive operation thereof, and means effective through said pivotal interconnection to move said instrumentality out of register with said function lever.

CHARLES W. BURCKY.
